US0D1029268S

(12) **United States Design Patent** (10) **Patent No.:** **US D1,029,268 S**
(45) **Date of Patent:** **** May 28, 2024**

(54) **PULSE OXIMETER**

(71) Applicant: **Wesper Inc.**, New York, NY (US)

(72) Inventor: **Jacob Bennett**, Brooklyn, NY (US)

(73) Assignee: **Wesper Inc.**, New York, NY (US)

(**) Term: **15 Years**

(21) Appl. No.: **29/838,535**

(22) Filed: **May 13, 2022**

(51) **LOC (14) Cl.** **24-02**

(52) **U.S. Cl.**

USPC **D24/167**; D24/187

(57) **CLAIM**

The ornamental design for a pulse oximeter, as shown and described.

DESCRIPTION

FIG. 1 is a front view of a pulse oximeter showing my new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a front-top perspective view thereof; and,

FIG. 8 is a front-bottom perspective view thereof.

The broken lines in the drawings depict portions of the pulse oximeter that form no part of the claimed design.

1 Claim, 8 Drawing Sheets
